UNITED STATES PATENT OFFICE

168,228

AUTOMOBILE

Karl Kleve, Cincinnati, Ohio

Application July 28, 1951, Serial No. 16,065

Term of patent 14 years

(Cl. D14—3)

To all whom it may concern:

Be it known that I, Karl Kleve, a citizen of the United States and a resident of Cincinnati, in the county of Hamilton and State of Ohio, have invented a new, original, and ornamental Design for an Automobile, of which the following is a specification, reference being made to the accompanying drawing, forming a part thereof.

In the drawing:

Figure 1 is a side elevational view of an automobile showing my new design.

Figure 2 is a perspective view taken from the left rear corner thereof.

Figure 3 is a front view thereof.

Figure 4 is a rear view thereof.

The rear fenders terminate in oval exhaust ducts as shown.

The dominant features of my design reside in the portions shown in full lines.

I claim:

The ornamental design for an automobile, substantially as shown and described.

KARL KLEVE.
